Primary Examiner — Angela J Lee*Assistant Examiner* — Audris Park(57) **CLAIM**

The ornamental design for a flashlight, as shown and described.

DESCRIPTION

FIG. 1 is a top view of a flashlight showing the claimed design;

FIG. 2 is a bottom view thereof;

FIG. 3 is a left side view thereof;

FIG. 4 is a right side view thereof;

FIG. 5 is a front view thereof;

FIG. 6 is a back view thereof;

FIG. 7 is a perspective view of the front and top thereof;

FIG. 8 is a perspective view of the front and bottom thereof; and,

FIG. 9 is a perspective view of the back and bottom thereof. The broken lines shown are included for the purpose of illustrating portions of the flashlight that form no part of the claim. The shading lines in the drawings show contour and are not intended to indicate surface ornamentation.
